United States Patent Office.

M. J. RHEES, M. D., OF MOUNT HOLLY, NEW JERSEY.

Letters Patent No. 70,616, dated November 5, 1867.

IMPROVEMENT IN PESSARY.

The Schedule referred to in these Letters Patent and making part of the same.

TO ALL WHOM IT MAY CONCERN:

Be it known that I, M. J. RHEES, M. D., of Mount Holly, in the county of Burlington, and State of New Jersey, have invented a new and improved Pessary; and I do hereby declare that the following is a full, clear, and exact description thereof, which will enable those skilled in the art to make and use the same, reference being had to the accompanying drawings, forming part of this specification.

The present invention relates to a pessary or support to be used as a support and covering to the mouth of the uterus in cases of female weakness, falling of the womb, and other affections of the same; and the invention consists in providing the common *ff*-shaped pessary with a rest or support for the womb, which rest or support may be in the form of a concave perforated disk, or globe, or ovoid, flattened on its superior or upper surface. In the accompanying plate of drawings my improved pessary is illustrated—

Figure 1 being a view of the same from its front side, and

Figure 2 an edge view.

Similar letters of reference indicate corresponding parts.

A, in the drawings, represents my improved pessary. This pessary is in its edge view and at its posterior end of a similar shape to the ordinary *ff* pessary now in common use, but at its superior or upper end or extremity is made broader than in such pessaries, and is there provided with a rest or support, B. This rest B is concave upon its upper face C, and in shape, in the present instance, is shown as ovoid, but may be globular or other form suitable.

A pessary constructed as above described is most simple and perfect, and in its shape is such as to have no angles, joints, or ends to produce irritation of the parts.

I claim as new, and desire to secure by Letters Patent—

A pessary, made substantially as described.

M. J. RHEES.
